US00D609352S

(12) **United States Design Patent**
Kitayama

(10) **Patent No.:** **US D609,352 S**
(45) **Date of Patent:** **** Feb. 2, 2010**

(54) **PROBE FOR ULTRASONIC DIAGNOSIS APPARATUS**

(75) Inventor: **Masahiko Kitayama**, Mitaka (JP)

(73) Assignees: **Kabushiki Kaisha Toshiba** (JP);
Toshiba Medical Systems Corporation (JP)

(**) Term: **14 Years**

(21) Appl. No.: **29/334,663**

(22) Filed: **Mar. 31, 2009**

(30) **Foreign Application Priority Data**

Oct. 31, 2008 (JP) 2008-028134

(51) **LOC (9) Cl.** **24-02**

(52) **U.S. Cl.** **D24/186**

(58) **Field of Classification Search** D24/107, D24/141, 158, 164, 165, 167, 170, 186-187, D24/231; D10/57, 60, 78, 80; 600/407, 600/461, 459; 378/98.7, 98.8, 189

(57) **CLAIM**

The ornamental design for a probe for ultrasonic diagnosis apparatus, as shown and described.

DESCRIPTION

FIG. 1 is a front, bottom and right side perspective view of a probe for ultrasonic diagnosis apparatus, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines shown are included for the purpose of illustrating a portion of the probe for ultrasonic diagnosis apparatus that forms no part of the claimed design.
